CLAIM

The ornamental design for a sandal, as shown and described.

DESCRIPTION

FIG. 1 is a front and top perspective view of a sandal, showing my new design;

FIG. 2 is a rear and bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof; and,

FIG. 9 is an enlarged perspective view of detail “9” identified in FIG. 1.

The dashed lines in the figures illustrate portions of the sandal that form no part of the claimed design. The dash dot dash lines in FIGS. 1 and 9 are for the purpose of illustrating the enlarged view indicators and form no part of the claimed design.

1 Claim, 9 Drawing Sheets
